Primary Examiner — Eliza Z Harvey*Assistant Examiner* — Landon Thomas Cassell(74) *Attorney, Agent, or Firm* — Chris Tanner; Jared Doster; BlueCollarIP.com(57) **CLAIM**

The ornamental design for a massage gun roller, as shown and described.

DESCRIPTION

FIG. 1 is a rear, top perspective view of a massage gun roller showing my new design;

FIG. 2 is a front, top perspective view thereof;

FIG. 3 is a left side elevation view thereof;

FIG. 4 is a front elevation view thereof;

FIG. 5 is a right side elevation view thereof;

FIG. 6 is a rear elevation view thereof;

FIG. 7 is a top elevation view thereof; and,

FIG. 8 is a bottom elevation view thereof.

The evenly-spaced broken lines in the drawings depict portions of the massage gun roller that form no part of the claimed design.
